(57) **CLAIM**

The ornamental design for a toy snake as shown and
described.

DESCRIPTION

FIG. 1 is a top, front, left perspective view of a toy snake
showing the new design;

FIG. 2 is a top, rear, right perspective view thereof;

FIG. 3 is a bottom, front, right perspective view thereof;

FIG. 4 is a bottom, rear, left perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The dashed lines shown in the drawings illustrate portions of
the toy snake that form no part of the claimed design.

1 Claim, 8 Drawing Sheets
